DOOR CLOSER AND CHECK

Gustav H. Anderson, New Britain, Conn., assignor
to The Hart & Hutchinson Company, New
Britain, Conn., a corporation of Connecticut

Application April 23, 1932, Serial No. 607,155

12 Claims. (Cl. 16—61)

This invention relates to door closers and checks, and more particularly to a device of this nature adapted to be concealed within a door or door jamb.

5 One object of this invention is to provide a door closer and check of the above nature in which the door is closed by a strong coiled spring, and the action of said spring is retarded by a piston working against a liquid of high viscosity forced through a restricted passage.

A further object is to provide a door closer and check of the above nature in which the resistance to the door closing spring will be substantially uniform during the entire door swing, except at the end of the closing movement when the resistance to said spring will be suddenly released to insure the proper latching of the door.

A further object is to provide a door closer and check of the above nature consisting of two superposed cylinders having a valve controlled by-pass therebetween.

A further object is to provide a device of the above nature in which the upper cylinder contains a floating piston and the lower cylinder a spring actuated piston having flexible connection with a stationary door jamb.

A further object is to provide a construction of this nature in which the viscous fluid is confined at all times in the space in the cylinders between the two moving pistons, thus eliminating air pockets due to the tendency of the liquid to seek its own level.

A further object is to provide a door closer and check of the above nature in which the speed of closing the door may be regulated by means of a needle valve adjustable from the exterior, and also in which the increased pressure at the end of the door closing movement may be eliminated in cases where there is no door latch.

40 A further object is to provide a door closer and check of the above nature which will be simple in construction, inexpensive to manufacture, easy to install and manipulate, compact, and very efficient and durable in use.

45 With these and other objects in view there has been illustrated on the accompanying drawing one form in which the invention may be conveniently embodied in practice.

In the drawing:

50 Fig. 1 represents a fragmentary horizontal sectional view through a door and door frame, showing a door closer and check assembled therein.

Fig. 2 is a side elevation view of the door closer and check detached from the door.

Fig. 3 is a rear end view of the same.

Fig. 4 is a longitudinal sectional view of the same.

Fig. 5 is an enlarged fragmentary longitudinal sectional view through the inner or front end of 60 the door closer and check, showing the valve mechanism as it appears just after the resistance to the closing spring has been released to permit latching of the door.

Fig. 6 is a transverse sectional view taken along 65 the line 6—6 of Fig. 4.

Fig. 7 is a detail perspective view of the sliding check valve releasing plate.

Referring now to the drawing in which like reference numerals denote corresponding parts 70 throughout the several views, the numeral 10 indicates a door adapted to be pivotally supported within a door frame or casing 11, by means of hinges 12. A deep recess 13 is provided in the rear section of the door 10 to receive a door closer 75 and check device generally indicated by the numeral 14. The door closer and check 14 consists of a pair of tubular cylinders 15 and 16 located one above the other in spaced parallel relationship, as best shown in Figs. 2 and 4. The 80 front ends of the cylinders 15 and 16 are connected to each other by means of a spacing block 17, which is permanently secured to the outer peripheries of said cylinders in any suitable manner, as by soldering. The rear end of the upper 85 cylinder 15 is tightly seated upon a round supporting block 18, which is detachably secured to a door face plate 19, as by a screw 18a engaged in a tapped hole 18b concentrically formed in said block 18. The rear end of the lower cylinder 90 16 is similarly attached to a reduced turned section 20 of a square support block 21 which is detachably secured to the face plate 19, as by a pair of screws 22.

The face plate 19 is adapted to support and hold the door closer unit 14 within the recess 13, and said plate may be secured to the rear edge of the door 10 as by wood screws adapted to fit in four beveled countersunk holes 23 provided in the corners of said face plate, as clearly shown in Fig. 3. 100

The front end of the upper cylinder 15 is tightly sealed by means of a thick disc or plug 24. The plug 24 is provided with a concentric tapped hole through which the cylinders 15 and 16 may be charged with a liquid of suitable viscosity, and 105 said tapped hole is adapted to be sealed by a screw 25, a leak-preventive leather washer 26 being interposed between the head of said screw and the plug 24.

A floating piston 27 is adapted to be freely re- 110

ciprocated by suction within the upper cylinder. The floating piston 27 preferably consists of a solid cylindrical block 28 having a pair of oppositely arranged hat leathers 29 and 30 detachably secured to the opposed faces of said block 28 by means of a pair of metal washers 31 and 32 fitting within the crown of said hat leathers 29 and 30, and a pair of fillister screws 33 and 34 screwed within a tapped hole 35 centrally located 10 in said block 28. As shown in Fig. 4, the floating piston divides the upper cylinder 15 into two compartments 36 and 37. The left-hand compartment 36 is an air compartment which is adapted to be freely vented at all times through a longitudinal bore 38 in the rear cylinder support block 18, said bore being in alignment with a vent hole 39 provided in the face plate 19. The right-hand compartment 37 is a liquid reservoir which is completely filled at all times regardless of the varying capacity of said compartment 37 due to the movement of the floating piston 27.

In the lower cylinder 16 provision is made of a spring actuated piston 40 consisting of a solid cylindrical block 41 having a pair of oppositely extending reduced sections 42 and 43. The front reduced section 43 is provided with a suitable non-leakable packing in the form of a pair of inverted juxtaposed hat leathers 44 and 45 adapted to be suitably reinforced by a pair of metal washers 46 and 47 and detachably secured to said reduced section 43, as by a cap screw 48.

The rear reduced section 42 is pivotally attached to a connecting link 49 which in turn is pivotally secured to the inner extremity of a specially constructed non-kinkable chain 50, which was fully described in applicant's prior pending application, Serial No. 516,641, filed February 18, 1931. The chain 50 is adapted to be guided through a rectangular aperture 51 cut in the face plate 19 and support block 20 by means of a roller 50a pivoted on a vertical pin 50b in said block 20. The outer end of said chain 50 is provided with suitable anchorage in a jamb plate 52 secured to the door frame 11, as clearly shown 46 in Fig. 1.

In order to press the piston 40 forwardly at all times into a liquid filled chamber 53, provision is made of a strong helical compression spring 54, one end of which abuts against the turned section 20 of the supporting block 21, and the other end is adapted to seat upon a shoulder formed by the reduced section 42 of the piston block 41.

Valve mechanism

The valve mechanism of the door check is located in the front of the chamber 53 of the bottom cylinder 16, as clearly shown in Figs. 4 and 5, and consists of a valve block 55 tightly fitted within the chamber 53 a short distance from the front extremity of said cylinder 16. The valve block 55 is provided with an integral forwardly extending reduced shank 56 permanently secured within a concentric disc or plug 57, which is adapted to seal the end of the lower cylinder 16. By means of this construction, it is obvious that an annular compartment 58 is formed in the front of the cylinder 16 surrounding the shank 56. This compartment 58 has a suitable passageway leading to the upper compartment 37 consisting of a relatively large vertical hole 59 drilled through a T-connection 60 integral with the spacing block 17. As shown in Figs. 4 and 5, the T-connection 60 is adapted to 75 protrude through suitable apertures provided in

adjacent cylindrical surfaces of the cylinders 15 and 16. The annular compartment 58 communicates with the chamber 53 in the lower cylinder 16, by means of a longitudinal tubular passage 61 eccentrically located in the lower part of the valve block 55.

In order to prevent the flow of liquid through the passage 61 when the piston 40 is being retracted by the compression spring 54, provision is made of a ball check valve 62 which is adapted to seat against the sharp annular front edge of the passage 61. The ball valve 62 is loosely held within a ball retaining cage 63 rigidly secured to the front face of the valve block 55.

Obviously with the passage 61 tightly sealed by the ball valve 62, it will be necessary for the fluid to seek a different passage back into the upper cylinder 15, which is accomplished by means of a by-pass port 64 opening into the chamber 53. The port 64 leads into a needle valve chamber 65 having access to the chamber 37 through a reduced bleed hole 66 leading into the vertical passage 59 in the T-connection 60.

In order to permit the adjustment of the door closing speed, a tapered needle pin 67 is adjustably fitted within the needle valve chamber 65 and is attached to the inner threaded end of an elongated adjusting rod 68 disposed between the two cylinders and having threaded engagement within the spacing block 17, as clearly shown in Fig. 4. The operating end of the needle valve rod 68 is rotatably supported in an aperture 69 formed in the face plate 19, and said rod 68 is provided with an end slot 70 for receiving a screw driver for adjusting the needle valve pin 67.

In order to permit a sudden release of the fluid pressure in the chamber 53 at the end of the closing stroke of the piston 40 for the purpose of latching the door 10, provision is made of a vertically sliding valve releasing plate 71, which is adapted to be loosely held against the front face of the valve block 55 by means of the retaining cage 63, as clearly shown in Figs. 4 and 5. As shown in the detail view of Fig. 7, the valve releasing plate 71 is provided with a key-hole slot 72, said slot 72 consisting of a small upper semi-circular aperture 73 merging into a larger spherically cupped aperture 74 suitably formed to loosely fit the contour of the ball valve 62.

The releasing plate 71 is adapted to be vertically raised at a predetermined time from the position shown in Fig. 4 to the position shown in Fig. 5 by means of a plunger pin 75 adjustably secured in a tapped hole provided in the piston cap screw 48, said pin 75 being locked in adjusted position by means of a small set screw 48a threadedly engaged in a tapped hole provided in the head of said cap screw.

The pin 75 is provided with a tapered extremity 76 and on the return stroke of the piston 40 will pass through an aperture 63a in the retaining cage 63, and also through the semi-circular aperture 73 of the key-hole slot 72 causing the plate 71 to ride over the tapered extremity 76 and upon the top surface of the pin 75, which action will cause the ball valve 62 to roll out of the spherically cupped aperture 74, thus unseating the valve 62 from the opening in the tubular passage 61, as clearly shown in Fig. 5. When the plunger pin 75 is in its foremost position, it will be loosely fitted within an elongated cavity 77 concentrically formed in the valve block 55.

Operation

In operation, when the door 10 is swung from

closed to open position, the piston 40 will approach the rear of the cylinder 16, causing the helical spring 54 to be compressed, as shown in Fig. 4. This movement of the piston 40 will 5 create a vacuum within the chamber 53, and cause the ball check valve 62 to move to the left within the cage 63 and unseat itself from the front opening in the passage 61. The liquid will thus be permitted to flow freely from the front compartment 37 in the upper cylinder 15 through the aperture 59, the annular compartment 58, and the tubular passage 61 into the liquid chamber 53. Simultaneously with the rearward motion of the piston 40 in the lower cylinder 16, the floating 10 piston 27 in the upper cylinder 15 will move forwardly due to the liquid being drained out of the compartment 37 and the action of atmospheric pressure on the rear of said piston 27.

It will thus be seen that relatively little resistance will be offered to the opening of the door 10, but as soon as the door is released, the ball check valve 62 will be forced back against its seat in the opening of the tubular passage 61, and further movement of the piston 40 to the right under the influence of the spring 54 will be retarded by reason of the fact that the liquid in the chamber 53 is caused to flow through the by-pass port 64, the needle valve chamber 65, and the relatively small bleed hole 66, whereby the closing of the door will 20 be cushioned to the desired extent.

The needle valve pin 67 may, of course, be so adjusted with respect to the valve chamber 65 to obtain any desired closing speed. Near the completion of the return stroke of the piston 40, the pressure in the chamber will be suddenly released by the cooperating valve releasing plate 71 and pin 75 which causes the ball check valve 62 to unseat and allow unrestricted flow of liquid back into the upper chamber 37, thus permitting the 30 door 10 to be shut quickly at the end of its swing into latching engagement.

If the door 10 is constructed without a latch, it will be unnecessary to release the pressure of the spring at the end of the closing stroke of the piston. In this case the pin 75 may be readily removed by unscrewing it from the cap screw 48.

While the door closer and check 14 has been herein disclosed as located within the door 10, it will be understood that it is within the spirit and scope of the present invention to reverse this arrangement and locate said door closer and check 10 within the door casing 11 and fasten the chain 50 to the rear edge of the door 13.

While there has been disclosed in this specification one form in which the invention may be embodied, it is to be understood that this form is shown for the purpose of illustration only, and that the invention is not to be limited to the specific disclosure but may be modified and embodied 55 in various other forms without departing from its spirit. In short, the invention includes all the modifications and embodiments coming within the scope of the following claims.

Having thus fully described the invention, what is claimed as new, and for which it is desired to secure Letters Patent, is:

1. In a door closer and check, a pair of cylinders, a floating piston in one cylinder and having one side in contact with a liquid and pressed by the atmosphere on its other side, a spring actuated piston in the other cylinder, means for connecting said cylinders, said cylinders containing a liquid between said pistons, flexible means for connecting said spring actuated piston with a door

casing, and means to permit a restricted flow of liquid from one cylinder to the other to check the closing of said door.

2. In a door closer and check, a pair of parallel cylinders placed one above the other, a floating piston in the upper cylinder for dividing said cylinder into two chambers, one an air chamber open to the atmosphere and the other a liquid chamber, a spring actuated piston in the lower chamber, flexible means for connecting said lower piston with a door casing, a spring within said lower chamber for urging said piston to closed position, a liquid within said cylinders in contact with one side of each piston, means for allowing an unrestricted flow of liquid from one cylinder to the other during the opening of the door, means to permit a restricted reverse flow of liquid within the cylinder to check the closing of the door, and means for adjusting the restricted reverse flow of liquid for changing the speed of closing the door. 80

3. In a door closer and check, a pair of parallel cylinders located one above the other, a spacing block located adjacent one end of said cylinders for separating the same, a face plate connecting the other end of said cylinders, a floating piston fitted within the upper cylinder and having one side in contact with the atmosphere, a spring-pressed piston fitted within the lower cylinder, a liquid within said cylinders filling the space between said pistons, flexible means for 85 connecting the lower piston with a door casing, means in said spacing block for allowing unrestricted flow of oil between said cylinders during the opening of the door, and means in said block to restrict the flow of liquid between said chambers during the closing of said door. 90

4. In a door closer and check, a pair of parallel cylinders, a spacing block for holding said cylinders in separated relation, a face plate attached to one end of said cylinders, a floating 100 piston in said upper cylinder for dividing said cylinder into an air and a liquid compartment, an atmospheric vent hole leading into said air compartment, a piston fitted within the lower cylinder, a spring within said lower chamber for 105 urging said piston to closed position, flexible means for connecting said lower piston with a door casing, means for allowing an unrestricted flow of liquid from one cylinder to the other during the opening of the door, means to restrict 110 the reverse flow of liquid during the closing of the door, and means for releasing the flow restricting means at a predetermined time for permitting the spring to snap the door suddenly into latching engagement. 115

5. In a door closer and check, a pair of parallel cylinders placed one above the other, a floating piston in the upper cylinder for dividing said cylinder into an atmospheric compartment and a liquid filled compartment, a spring-pressed piston, a chain of limited flexibility connected to the rear of said lower piston, anti-friction means for guiding said chain through the rear of said lower cylinder, means for attaching the outer end of said chain to a door casing, means for permitting 120 an unrestricted flow of liquid from one cylinder to the other during the opening of the door, and means for permitting a restricted reverse flow of liquid between said cylinders during the door closing operation. 125

6. In a door closer and check, a pair of parallel cylinders located one above the other, a floating piston in said upper cylinder, the space in front of said floating piston being filled at all times with liquid, means to permit the atmosphere to press 130

on the rear of said floating piston, a spring-pressed piston fitted within said lower cylinder, flexible means for connecting said latter piston with a door casing, the space in front of said lower piston being filled at all times, and a liquid filled passage connecting the front ends of said cylinders.

7. In a door closer and check, a pair of parallel cylinders located one above the other, a floating piston in the upper cylinder and having one side in contact with the atmosphere, a spring actuated piston fitted within the lower cylinder, flexible means for connecting the lower piston with a door casing, a liquid completely filling the space in said cylinders between said pistons, means for connecting the interior of said cylinders for permitting an unrestricted flow of liquid between said cylinders when the door is being opened, and means between said cylinders for restricting the reverse flow of liquid when the door is being closed.

8. In a door closer and check, a pair of parallel cylinders located one above the other, a floating piston in the upper cylinder, a spring actuated piston fitted within the lower cylinder, flexible means for connecting the lower piston with a door casing, a liquid completely filling the space in said cylinders between said pistons, means for connecting the interior of said cylinders for permitting an unrestricted flow of liquid between said cylinders when the door is being opened, adjustable means between said cylinders for restricting the reverse flow of liquid when the door is being closed, and valve means in the lower cylinder for releasing the restriction on the reverse flow of liquid at a predetermined time.

9. In a door closer and check, a pair of parallel cylinders located one above the other, a floating piston in the upper cylinder and having one side in contact with the atmosphere, a spring actuated piston fitted within the lower cylinder, flexible means for connecting the lower piston with a door casing, a liquid completely filling the space in said cylinders between said pistons, an unrestricted fluid passage connecting said cylinders, a restricted by-pass, a valve in said lower chamber for permitting the fluid to flow through said passage when the door is being opened, and means for diverting the liquid through said by-pass when said door is being closed.

10. In a door closer and check, a pair of parallel cylinders located one above the other, a floating piston in the upper cylinder, a spring actuated piston fitted within the lower cylinder, flexible means for connecting the lower piston with a door

with a door casing, a liquid completely filling the space in said cylinders between said pistons, an unrestricted fluid passage connecting said cylinders, a restricted by-pass, a valve in said lower chamber for permitting the fluid to flow through said passage when the door is being opened, and means for diverting the liquid through said by-pass when said door is being closed, said diverting means comprising a ball check valve adapted to close a valve passage when said door is being closed, and means connected to said piston means for unseating said valve just before the end of the stroke of said piston.

11. In a door closer and check, a pair of parallel cylinders located one above the other, a floating piston in the upper cylinder, a spring actuated piston fitted within the lower cylinder, flexible means for connecting the lower piston with a door casing, a liquid completely filling the space in said cylinders between said pistons, an unrestricted fluid passage connecting said cylinders, a restricted by-pass, a valve in said lower chamber for permitting the fluid to flow through said passage when the door is being opened, and means for diverting the liquid through said by-pass when said door is being closed, said diverting means comprising a ball check valve adapted to close a valve passage when said door is being closed, a sliding plate engaging said ball valve, and means carried by said piston for moving said plate at a predetermined time for unseating said ball valve and allowing an unrestricted reverse flow of liquid through said valve passage.

12. In a door closer and check, a pair of parallel cylinders located one above the other, a floating piston in the upper cylinder, a spring actuated piston fitted within the lower cylinder, flexible means for connecting the lower piston with a door casing, a liquid completely filling the space in said cylinders between said pistons, an unrestricted fluid passage connecting said cylinders, a restricted by-pass, a valve block located in said lower cylinder between said fluid passage and said by-pass, a valve controlled fluid passage in said block, a ball valve adapted to seat in said valve passage and prevent a reverse flow of liquid when the door is being closed, a ball retaining cage attached to said valve block, a vertical apertured plate engaging said ball valve, a rod attached to said spring actuated piston adapted to pass through said aperture and raise said plate to unseat said ball valve before the end of the stroke of said piston.

GUSTAV H. ANDERSON. 130
